STORAGE CONTAINER FOR AUTOMOBILE
CLEANING ACCESSORIES OR THE LIKE

Joseph T. Proietti, 1447 51st Ave., Cicero, Ill.

Filed May 28, 1962, Ser. No. 70,291

Term of patent 14 years

(Cl. D58—11)

FIGURE 1 is a side elevational view of a storage container for automobile cleaning accessories or the like showing my new design;

I claim:

The ornamental design for a storage container for automobile cleaning accessories or the like, substantially as shown.
